UNITED STATES PATENT OFFICE.

WILL F. HOLBROOK, OF SEWARD, NEBRASKA.

DESIGN FOR A SPOON.

SPECIFICATION forming part of Design No. 21,496, dated April 26, 1892.

Application filed February 1, 1892. Serial No. 419,998. Term of patent 7 years.

To all whom it may concern:

Be it known that I, WILL F. HOLBROOK, of Seward, Seward county, Nebraska, have invented and produced a new and original Design for Souvenir Spoons, of which the following is a full, clear, and exact description, reference being had to the accompanying drawings, forming a part hereof.

My invention relates to what are known as "souvenir spoons," and the leading features of my design are the head and bust of a man located at the upper end of the handle of the spoon, a circular strap surrounding a horseshoe, and an open-work ornament located also at the upper end of the handle of the spoon, a hypodermic syringe forming the spoon-handle, a pictorial illustration of two men and located in the bowl of the spoon, and representations of tobacco-pipes, drinking-bottles, opium-bottles, pipes and a package of cigarettes, a plug of chewing-tobacco, and drinking-glass variously disposed about the spoon-handle, as hereinafter fully described.

In order that the nature of my design may be clearly understood, I will proceed to describe it with reference to the accompanying drawings, in which—

Figure 1 is a front elevation of a spoon embodying my design. Fig. 2 is a rear elevation of the same.

In the said drawings, 1 designates the handle of the spoon, the said handle being in the form of a hypodermic syringe. At the upper end of this handle is a circular figure 3, simulating a strap or belt, the ends of which are connected by a figure 4, simulating a buckle. This circular figure apparently rests upon the knob or button 2 of the hypodermic

syringe, which apparently constitutes the handle of the spoon, and within the strap 40 is a figure simulating a horseshoe 5. This horseshoe apparently embraces an open-work ornament 6, and immediately above the circular figure 3 and apparently supporting a figure 7, simulating the head and bust of a 45 man, the face of this figure being turned obliquely toward the front side of the spoon. The bowl 8 of the spoon contains upon its front or concave surface a pictorial representation. At one side of the upper end of 50 the syringe, which apparently constitutes the handle of the spoon, is a figure 10, simulating a package of cigarettes, a plug of chewing-tobacco crossed with a tobacco-pipe. At the opposite side of the upper end of the handle or syringe is a figure 11, simulating a tobacco-pipe and several cigars. At one side of the opposite end of the syringe, which apparently forms the handle of the spoon, is a figure 12, simulating an opium-pipe, a bottle, 55 and a small syringe. At the opposite side of the lower end of the syringe, which apparently constitutes the handle of the spoon, is a figure 13, simulating a bottle, a flask, and a drinking-glass.

Having thus described my design, what I claim is—

The design for a spoon, as shown and described.

In testimony whereof I affix my signature in 70 the presence of two witnesses.

WILL F. HOLBROOK.
